UNITED STATES PATENT OFFICE.

HUGH W. SANFORD, OF KNOXVILLE, TENNESSEE, AND HARRY W. JONES, OF ST. LOUIS, MISSOURI, ASSIGNEES TO SANFORD INVESTMENT COMPANY, OF WILMING-
TON, DELAWARE, A CORPORATION OF DELAWARE.

HUB AND JOURNAL BOX.

Application filed June 8, 1925. Serial No. 35,670.

This invention relates generally to hubs and axle boxes or bearings and particularly to hubs and axle boxes or bearings in mine cars in which a part or all of the wheels are fixed on the axles and the axles rest in bearing which are associated with pedestals or housings attached to the car body.

The object of this invention is to provide a construction in which the bearing box and the pedestal or housing are associated with each other and with the wheel hub in an effective manner, particularly with reference to making the bearing box free from end thrust and making it "floating" and "self-aligning", and with reference to ample lubrication and exclusion of dirt.

In the accompanying drawings,

Fig. 1 is a plan of the under structure of a mine car embodying our improvement;

Fig. 2 is a perspective view of one end of one of the transverse channel plates which are applied to the lower face of the car bottom;

Fig. 3 is a longitudinal upright section on the line, 3—3, of Fig. 1, looking in the direction of the arrow;

Fig. 4 is an upright section on the line, 4—4, of Fig. 3, looking toward the right;

Fig. 5 is an upright section on the line, 5—5, of Fig. 3, looking toward the right;

Fig. 6 is an upright section on the line, 6—6, of Fig. 3, looking toward the right;

Fig. 7 is an upright section on the line, 7—7, of Fig. 3, looking toward the left;

Fig. 8 is an upright section on the line, 8—8, of Fig. 3, looking toward the right;

Fig. 9 is an upright section on the line, 9—9, of Fig. 3, looking toward the left;

Fig. 10 is an upright section on the line, 10—10, of Fig. 3, looking toward the left;

Fig. 11 is an upright section on the line, 11, 12—11, 12, of Fig. 3, looking toward the right;

Fig. 12 is an upright section on the line, 11, 12—11, 12, of Fig. 3, looking toward the left;

Fig. 13 is an upright section on the line, 13—13, of Fig. 3, looking toward the right;

Fig. 14 is a horizontal section on the line, 14—14, of Fig. 3;

Fig. 15 is a horizontal section on the line, 15—15, of Fig. 3, the hub being omitted; Fig. 16 is a perspective of the bearing box lining;

Fig. 17 is a perspective of the bearing box; 55
Fig. 18 is a perspective of the housing.

Referring to said drawings, A, A are axles, G, G, are wheels having hubs, G¹, surrounding the axles. The axles extend through the pedestals or housings, C. B², B³ 60 are two cross plates. Each of these plates is slotted or cut out at each end to leave two arms, B⁴, in which are holes, B⁵, and which arms have outer, downward-directed marginal flanges, B⁶. The space between these 65 arms is made right to bring one of the arms close to each side of the recess, B¹, in the floor, B, and the sides of the pedestals, C, and to bring the edge of the plate which is between the arms close to the pedestal. Between the plates, B³, are two connecting members, I, each having its ends rigidly joined to the adjacent flanges, B⁶, of the plates, B³. In the form shown in the drawings, each of said members is angle-form in cross section and has one of its flanges, I¹, directed downward and placed toward the wheels, G. The horizontal flange of each member, I, is cut just long enough to adapt its ends to bear against the adjacent flange, 70 B⁶, of the adjacent cross plate, while the upright flange, I², is left long enough to be bent at right angles to the length of the member, I, so as to form a tongue, I², lying flatwise against the adjacent flange, B⁶, and secured thereto by a rivet, I⁴. The two cross members, B³, and the connecting members, I, form a rectangular frame which becomes 75 a part of the truck or under structure of the car. Near each wheel each of said flanges, I¹, is provided with an orifice, I³, large enough to receive a lubricating pipe hereinafter described.

A pedestal or housing, C, is attached to each end of each cross plate, B³. The cross plates being definitely spaced from each other by the connecting members, I, the pedestals are held in definite relation to each other, the pedestals on one plate, B³, being on the same axial line, and the axial line of 100

the pedestals on one plate being held parallel to the upright plane of the axial line of the pedestals on the other plate.

The part of each axle which extends 5 through the wheel and through the axle bearing or bearing box is cylindrical and of uniform diameter. The entire axle is preferably of this form, in order that it may be made of cold drawn steel, a process which is 10 economical and also affords steel of high quality, whereby an axle of a given diameter is made stronger than can be made of hot rolled commercial steel.

B is the floor of the car body. In the 15 form shown by the drawings, this floor is of wood. Its lower face is recessed at B¹ to make room for the pedestal or housing, C, which surrounds the axle bearing or axle box body, D. The upper part of said pedestal has a horizontal face, C¹, resting 20 against the wood floor, as shown by Figs. 4, 5, 7, 8 and 9. On the floor above the recess, B¹, is a metal washer plate, B², through 25 which extend four bolts, as will appear further on.

On each side of the pedestal and integral therewith are two lugs, C², which bear upward and sidewise against the adjacent arms, B⁴. Bolts, B⁷, extend downward through 30 the washer plate, B², the floor, B, the adjacent arm, B⁴, and the adjacent lug, C², and bind said parts to each other. The drawings show four such bolts applied to the pedestal.

35 The pedestal or axle box housing, C, extends entirely around the axle box body. The inner end of the pedestal has an upright wall, C³, which has an oblong orifice, C⁴, the longer axis of which is upright. The 40 size of this orifice is sufficient to receive the axle, A, and to permit limited up and down movement of the axle in the housing.

The outer end of the housing, the end 45 nearest the wheel, has no upright wall integral with the housing. A removable thrust wall, F, surrounds the axle and extends across the end of the housing and is secured thereto by cap screws, C⁵, extending through the thrust wall and into the adjacent lugs, C², of the housing. The thrust wall has an oblong opening, F¹, through which the axle, A, extends. The long axis of said opening is upright; and said opening is only large enough to receive the axle and permit 50 limited up and down movement of the axle relative to the thrust wall and housing.

Between the inner end of the axle box, D, and the end wall, C³, of the housing, a dust 55 excluding washer plate, C⁸, surrounds the axle, A. A coiled spring, C⁹, surrounds the axle between the washer plate and the end wall, D⁸, and presses the washer plate yieldingly against the wall, C³, of the housing. By this means, the oblong opening, C⁴, in 60 the end wall, C³, of the housing is substan-

tially sealed against entry of dust from the outside of the housing. This exclusion of dust from the housing is important because the housing is used for holding in its lower part a supply of lubricant.

Between its ends, the upper face of the axle box, D, has a transverse horizontal ridge or summit, D¹, resting against the lower face of the upper wall of the pedestal or housing, C. Said ridge or summit is 70 transverse to the bearing box axis and forms a line on which the bearing box may relatively rock on the lower face of the upper wall of the housing, this feature contributing to making this a self-aligning axle bearing, such as is already known in this art. The rocking above mentioned is on a horizontal face. On each side of the bearing box are two upright faces which bear against corresponding faces, C⁶, on the inner side 75 faces of the housing, C. These faces, D² and C⁶, permit the relative rocking of the axle box above described, but limit rocking of the axle box relative to the housing on an upright axis.

90 The inner or right-hand end of the bearing box has an upright wall, D³, which fits closely around the axle but permits free turning and the passage of lubricant.

The opposite or outer end of the axle box 95 has no end wall formed integral with said body. A ring, D⁴, surrounds the axle and bears against the end of said box. The main part of said ring is in a plane transverse to the axle. Said ring has an outer 100 flange, D⁵, which extends over a part of the inner face of the box. Parts, D⁶, of said flange are bent into recesses, D⁷, formed on the outer face of the axle box. (Figs 3 and 9). By this means, said ring is removably secured to the axle box. Midway between its ends the interior face of the axle box has a circumferential channel, D⁸. A metal sleeve, D⁹, forms a lining for the axle box. Said sleeve extends over the channel, D⁸. 110 But said sleeve has a slot, D¹⁰, extending lengthwise and crossing the channel, D⁸, whereby lubricant in the channel may pass through said slot. Antifriction rollers, E, occupy the space between the axle, A, and the sleeve, D⁹. The ends of said rollers almost meet the wall, D⁸, and the ring, D⁴. Thus said ends are not engaged and are free 115 from end thrust.

120 Adjacent each wheel, G, a lubricant pipe, D¹¹, extends through the orifice, I³, of the adjacent connecting member, I, and toward the opposite connecting member. Said pipe is flexible and enters a nipple, D¹², which extends through a slot, C⁷, in the housing, C, 125 and is threaded into the side of the axle box midway between the ends of the latter and at the channel, D⁸, whereby lubricant may pass through the pipe, D¹¹, into said channel and thence through the slot, D¹⁰, in the 130

sleeve, D⁹, to the anti-friction rollers, E. A dust excluding plate, D¹³, surrounds the nipple, D¹², and covers the slot, C⁷. A disc, D¹⁴, is threaded around the outer end of the nipple, D¹² (Figs. 4, 7, 8 and 10). Between said disc and the plate, D¹³, is a coiled spring, D¹⁵, bearing against said disc and the plate, D¹³, whereby the plate, D¹³, is yieldingly pressed against the outer face of the housing for the exclusion of dust from the interior of the housing. The slot, C⁷, is for the purpose of allowing the nipple, D¹², to move relative to the housing when the axle box moves up or down in the housing.

On the outer end of the lubricant pipe, D¹¹, is any suitable device adapted to receive and transmit lubricant into said pipe. This may be a nipple or screw plug, D¹⁶, of well-known form for connection with a grease gun. The orifice, I⁸, in the connecting member, I, is to be far enough away from the adjacent axle to bring the outer end of the pipe, D¹¹, out of the range of the adjacent wheel, G, in order that lubricant may be injected into the axle box without passing between spokes or any other opening in the wheel and without the necessity of turning the wheel into any particular position on the axle.

The thrust wall, F, has a longitudinal flange, F², extending outward around the adjacent end of the hub, G¹, a space being left between the flange and the hub. A transverse flange, F³, extends from the flange, F², toward the hub. At the outer side of the flange, F³, dust excluding rings, F⁴, surround the hub and bear against said flange. Retaining pins, F⁵, extend through the outer part of the flange, F², at opposite sides of the hub and bear against the outer of the rings, F⁴, whereby said rings are held against the flange, F³, for the exclusion of dirt from the outside and to prevent escape of oil outward through the space between the hub and the flange, F³. A port, F⁶, through the lower part of the thrust wall, F, connects the interior of the housing, C, with the space between the thrust wall, F, and the transverse flange, F³. Lubricant may pass from the interior of the housing through said port into said space. In said space, two washers, F⁷, surround the axle, A. The diameter of said washers is less than the space enclosed by the flange, F², but the washers have radial wings, F⁸, which reach approximately to the inner face of the flange, F². The flange, F³, is slotted at F⁹, to allow said wings to pass for the insertion of said rings. (Figs. 12 and 13). At the left of the flange, F³, is the space for passing the rings.

Lubricant passing into the space between the anti-friction rollers, E, may pass along the axle at either end of the axle box and thence down into the lower part of the hous-

ing and accumulate there to the height of the lower part of the orifice formed by the flange, F³. Thus lubricant will be in the lower part of the path of the wings, F⁸, of the washers, F⁷. Said washers will turn irregularly by frictional engagement with the wheel hub. During such turning, the wings, F⁸, will carry or drive lubricant upward to and above the axle, whereby the meeting faces of the hub and the washers will be lubricated.

Ordinarily the wheel, G, will be made fast on the axle by means of a pin extending through the axle and the wheel hub at A¹. If the wheel is to be "loose", the pin is to be removed from A¹, and that or another pin inserted through the axle at A², for holding the wheel against outward movement on the axle. When the wheel is loose, lubricant is to be inserted through the port, G², into the lubricant passage, G³.

When the car body shifts toward the left, the end thrust is taken by the thrust wall, F, and the wheel hub, G¹, and the washers, F⁷, intermediate said members. Thrust in the opposite direction is taken by the thrust wall and the wheel hub at the other end of the axle.

The pedestal or housing, C, and the thrust wall, F, may be regarded as together constituting a housing structure which completely surrounds the axle box and through which the axle extends and which is adapted to retain lubricant and to exclude dust, lubricant first passing through the lubricant pipe, D¹¹, into the axle box and some of the lubricant afterward escaping into the lower part of the interior of the housing structure and thence into the annular recess in which are the washers, F⁷.

We claim as our invention,

1. In a railway car, the combination with an axle and a wheel surrounding the axle, of an axle box surrounding the axle, a housing structure surrounding the axle box and closed for retaining lubricant and excluding dirt and comprising an upright annular recess communicating at its lower part with the lower part of the interior of the portion of the housing in which the axle box is located, and means in said annular recess for carrying lubricant upward from the lower part of said recess, substantially as described.

2. In a railway car, the combination with an axle and a wheel surrounding the axle, of an axle box surrounding the axle, a housing structure surrounding the axle box and closed for retaining lubricant and excluding dirt and comprising an upright annular recess communicating at its lower part with the lower part of the interior of the portion of the housing in which the axle box is located, means in said annular recess for carrying lubricant upward from the

lower part of said recess, and a lubricant-conducting tube extending through the housing wall into the axle box, substantially as described.

5. 3. In a railway car, the combination with
an axle and a wheel surrounding the axle,
of an axle box surrounding the axle, a hous-
ing structure surrounding the axle box and
closed for retaining lubricant and exclud-
ing dirt and comprising an upright annular
recess communicating at its lower part with
the lower part of the interior of the por-
tion of the housing in which the axle box is
located, means in said annular recess for car-
rying lubricant upward from the lower part
of said recess, a lubricant-conducting tube
extending through the housing wall into the
axle box, and dust-excluding means sur-
rounding said tube at its entrance to the
20 housing, substantially as described.

4. In a railway car, the combination with
an axle and a wheel surrounding the axle,
of an axle box surrounding the axle, a hous-
ing structure surrounding the axle box and
closed for retaining lubricant and excluding
dirt, and a lubricant-conducting tube ex-
tending through the housing wall into the
25 axle box, substantially as described.

5. In a railway car, the combination with
an axle and a wheel surrounding the axle,
of an axle box surrounding the axle, a hous-
ing structure surrounding the axle box and
closed for retaining lubricant and excluding
dirt, a lubricant-conducting tube extend-
30 ing through the housing wall into the axle
box, and dust-excluding means surround-
ing said tube at its entrance to the housing, sub-
stantially as described.

6. In a railway car, the combination with
an axle and a wheel surrounding the axle,
of an axle box surrounding the axle, a hous-
ing structure secured to the car body and
surrounding the axle box and the axle and
closed for retaining lubricant and exclud-
ing dirt, said structure including a thrust
40 wall extending around the axle and over and
secured to one end of the housing body
and extending around the wheel hub and
having an annular recess communicating
with the lower part of the interior of the
45 housing, and washers in said annular recess
for carrying lubricant upward from the
lower part of said recess, substantially as
described.

7. In a railway car, the combination with
an axle and wheels surrounding the axle,
of an axle box surrounding the axle, a hous-
ing body secured to the car and surrounding
the axle box and the axle and closed below
50 for retaining lubricant and excluding dirt,
a thrust wall extending around the axle
and over one end of the housing body and
secured to the housing body and having a
flange extending horizontally over the wheel
55 hub and having on said flange an annular
recess communicating with the lower part
of the interior of the housing, and means
surrounding the flange and the housing
body for carrying lubricant upward from
60 the lower part of said recess, substantially as
described.

8. In a railway car, the combination with
an axle and a wheel surrounding the axle,
of an axle box surrounding the axle, a hous-
ing structure surrounding the axle box and
closed for retaining lubricant and excluding
dirt, a thrust wall extending around the axle
and over one end of the housing body and
secured to the housing body and having a
flange extending horizontally over the wheel
65 hub and having on said flange an annular
recess communicating with the lower part
of the interior of the housing, and means
surrounding the flange and the housing
body for carrying lubricant upward from
70 the lower part of said recess, substantially as
described.

9. In a railway car, the combination with
an axle and a wheel surrounding the axle,
of an axle box surrounding the axle, a hous-
ing structure surrounding the axle box and
closed for retaining lubricant and excluding
dirt, a thrust wall extending around the axle
and over one end of the housing body and
secured to the housing body and having a
flange extending horizontally over the wheel
75 hub and having on said flange an annular
recess communicating with the lower part
of the interior of the housing, and means
surrounding the flange and the housing
body for carrying lubricant upward from
80 the lower part of said recess, substantially as
described.

10. In a railway car, the combination with
an axle and a wheel surrounding the axle,
of an axle box surrounding the axle, a hous-
ing structure surrounding the axle box and
closed for retaining lubricant and excluding
dirt, a thrust wall extending around the axle
and over one end of the housing body and
secured to the housing body and having a
flange extending horizontally over the wheel
85 hub and having on said flange an annular
recess communicating with the lower part
of the interior of the housing, and means
surrounding the flange and the housing
body for carrying lubricant upward from
90 the lower part of said recess, substantially as
described.

inward-directed flange for the forming of an annular recess communicating with the lower part of the interior of the housing, washers in said annular recess for carrying lubricant upward from the lower part of said recess, dust-excluding means at the outer side of the inward-directed flange, and means for retaining said excluding means, substantially as described. 70

8. In a railway car, the combination with 75
an axle and wheels surrounding the axle, of
an axle box surrounding the axle, a housing
body secured to the car and surrounding the
axle box and the axle and closed below for
retaining lubricant and excluding dirt, a 80
thrust wall extending around the axle and
over one end of the housing body and se-
cured to the housing body and extending
over the wheel hub and having an annular
recess communicating with the lower part 85
of the interior of the housing, and washers
in said annular recess for carrying lubri-
cant upward from the lower part of said
recess substantially as described

9. In a railway car, the combination with 90
an axle and a wheel surrounding the axle,
of an axle box surrounding the axle, a housing
structure surrounding the axle box and
surrounding the axle at each end of the axle 95
box and surrounding the adjacent end of
the wheel hub and means on each end of the
housing structure for excluding dirt and the
housing structure having an annular recess
between the wheel hub and the axle box, the
lower part of said recess communicating 100
with the lower part of the housing structure
which contains the axle box, and means in
the annular recess for carrying lubricant up-
ward in said annular recess, substantially
as described. 105

10. In a railway car, the combination with
an axle and a wheel surrounding the axle,
of an axle box surrounding the axle, a hous-
ing structure surrounding the axle box and
surrounding the axle at each end of the axle
box and surrounding the adjacent end of the
wheel hub and means on each end of the
housing structure for excluding dirt and the
housing structure having an annular recess
between the wheel hub and the axle box, the
lower part of said recess communicating
with the lower part of the part of the hous-
ing structure which contains the axle box,
means in the annular recess for carrying
lubricant upward in said annular recess, and
a lubricant-conducting tube extending
through the housing wall, substantially as
described.

11. In a railway car, the combination with
an axle and a wheel surrounding the axle, of
an axle box surrounding the axle, a housing
surrounding the axle box and surrounding
the axle at each end of the axle box and sur-
rounding the adjacent end of the wheel hub
and means on each end of the housing struc-
125
130

ture for excluding dirt and the housing structure having an annular recess between the wheel hub and the axle box, the lower part of said recess communicating with the lower part of the part of the housing structure which contains the axle box, means in the annular recess for carrying lubricant upward in said annular recess, a lubricant-conducting tube extending through the housing wall, and dust-excluding means surrounding said tube at its entrance to the housing, substantially as described.

12. In a railway car, the combination with an axle and a wheel surrounding the axle, of an axle box surrounding the axle, a housing structure surrounding the axle box and closed for retaining lubricant and excluding dirt and the top of the axle box being engaged by the housing to permit rocking on an axle which is horizontal and parallel to the length of the car, and a lubricant-conducting tube extending through the housing wall into the axle box, substantially as described.

13. In a railway car, the combination with an axle and a wheel surrounding the axle, of an axle box surrounding the axle, a housing structure surrounding the axle box and closed for retaining lubricant and excluding dirt and the top of the axle box being en-

gaged by the housing to permit rocking on an axis which is horizontal and parallel to the length of the car, a lubricant-conducting tube extending through the housing wall into the axle box, and dust-excluding means surrounding said tube at its entrance to the housing, substantially as described.

14. In a railway car, the combination with an axle and a wheel surrounding the axle, of an axle box surrounding the axle, a housing structure surrounding the axle and closed for retaining lubricant and excluding dirt and positioned to bear endwise against the inner end of the hub of the wheel, and that end of the housing being open below the axle lower than the axle opening in the other end of the housing, in order that lubricant in the housing below the axle may enter the space between the housing and the wheel hub, substantially as described.

In testimony whereof I have signed my name at Washington, D. C., this 22nd day of May, in the year one thousand nine hundred and twenty-five.

HUGH W. SANFORD.

In testimony whereof, I have signed my name at Saint Louis, Missouri, this second day of June, 1925.

HARRY W. JONES.
